UNITED STATES PATENT OFFICE.

LOUIS GREENKY, OF NEW YORK, N. Y.

SUPPORT FOR HOISTING DEVICES.

No. 810,274.

Specification of Letters Patent.

Patented Jan. 16, 1906.

Application filed October 14, 1905. Serial No. 282,766.

To all whom it may concern:

Be it known that I, LOUIS GREENKY, a citizen of the United States, and a resident of the city of New York, borough of Manhattan, in the county and State of New York, have invented a new and Improved Support for Hoisting Devices, of which the following is a full, clear, and exact description.

The invention relates to hoisting devices used on buildings for hoisting safes, pianos, furniture, and other heavy articles at the outside of the building.

The object of the invention is to provide a new and improved support for hoisting devices, arranged to form a permanent part of the building, to permit convenient attachment and support of the hoisting-tackle employed for hoisting pianos, safes, furniture, and other heavy articles up to a window and through the same into a room of the building, and also for use by painters and other mechanics for supporting scaffolds, &c.

The invention consists of novel features and parts and combinations of the same, which will be more fully described hereinafter and then pointed out in the claims.

A practical embodiment of the invention is represented in the accompanying drawings, forming a part of this specification, in which similar characters of reference indicate corresponding parts in all the views.

Figure 1 is a sectional side elevation of the improvement as applied. Fig. 2 is a plan view of the same, parts being broken out. Fig. 3 is an enlarged cross-section of the improvement on the line 3 3 of Fig. 2. Fig. 4 is a perspective view of the shoe for the outer end of the hook-bar; and Fig. 5 is a perspective view of the chair for one of the roof-beams provided with sockets for the braces of the hook-bar.

The hook-bar A of the supporting device is preferably made of metal and is formed at its outer end into a hook A' for receiving and supporting a hoisting-tackle, and the inner end of the said hook-bar is in the shape of a fork, the members A² of which are fastened by bolts B to a roof-beam C of the building, the roof-beams resting on the usual front wall D of the building. The roof-beam C, between the roof-beams C, is provided with a chair E, resting on the wall D and formed

with sockets E' E² for receiving the lower ends of braces F F', provided at their upper ends with shoes G and G' for supporting the hook-bar A at points adjacent to the hook A' and at the beginning of the fork, as plainly illustrated in Fig. 1. The hook-bar A is inclined upwardly and outwardly from the shoe G' to the hook A', and the latter projects through the upper end of the cornice H, so that only the hook A' is visible, and consequently the device does not mar the appearance of the building on which it is used. As shown in Fig. 1, the hook-bar A, except the hook A', is covered by the roof-covering I, so as to keep the hook-bar well protected against rain, snow, and the like.

From the foregoing it will be seen that the supporting device for the tackle or other hoisting device forms a permanent fixture of the building, and hence is at all times in proper position to enable mechanics or other persons to conveniently connect the hoisting-tackle with the hook A' with a view to hoist safes, pianos, furniture, and other heavy articles at the outside of the building to a window, through which the article is passed to a room within the building.

By constructing the device in the manner described absolute safety is obtained, as the hook-bar is strongly supported by the braces and by its connection with the roof-beams.

The device is very simple and durable in construction, can be cheaply manufactured, and readily fastened in place at the time the building is being completed.

Having thus described my invention, I claim as new and desire to secure by Letters Patent—

1. A hoist-supporting device for buildings, comprising a hook-bar, and means for permanently securing the hook-bar to the building at the roof thereof, the hook of the said hook-bar projecting through the cornice of the building.

2. A hoist-supporting device for buildings, comprising a hook-bar having its outer end terminating in a hook and having its inner end forked and secured to roof-beams, the hook projecting beyond the face of the cornice of the building, a roof-beam chair and braces seated in the sockets formed therein.

3. A hoist-supporting device for buildings, comprising a hook-bar having its outer end

terminating in a hook and having its inner end forked and secured to roof-beams, the hook projecting beyond the face of the cornice of the building, a roof-beam chair and braces
5 seated in the sockets formed therein, each brace having a shoe for the hook-bar to rest on.
In testimony whereof I have signed my name

to this specification in the presence of two subscribing witnesses.

LOUIS GREENKY.
